UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

SELECTIVE SIGNALING SYSTEM.

1,244,998.

Specification of Letters Patent. Patented Oct. 30, 1917.

Application filed September 25, 1915. Serial No. 52,707.

To all whom it may concern:

Be it known that I, ALBEN E. LUNDELL, a citizen of the United States, residing at New York, in the county of Bronx and State of New York, have invented certain new and useful Improvements in Selective Signaling Systems, of which the following is a full, clear, concise, and exact description.

This invention relates to selective signaling systems, and more particularly to party-line telephone exchange systems.

It is the object of this invention to provide a selective signaling system in which signaling current sent to a station may be intercepted for actuating a special signal.

According to the main feature of this invention, means such as polarized or alternating current relays are provided for actuating a special signal at an attendant's position in response to the signaling of one or all stations associated with a telephone line, if one or all the stations are permanently disconnected or are transferred from one line to another line, the number of said alternating current or polarized relays being less than that of the stations. While the invention is disclosed as applied to a four-party line system, it will be obvious to those skilled in the art that it is equally well adaptable to selective signaling systems of widely varying character.

In the drawings, Figure 1 represents diagrammatically a calling substation, and an operator's cord circuit and calling device; in Fig. 2 there are shown, diagrammatically, selector switches used in the establishment of a connection to a party telephone line; and Fig. 3 represents a signaling apparatus for an attendant to indicate the existence of an intercepted call.

The disclosure of the telephone system is simplified as the means used for the establishment of a connection or the automatic selection of characteristic signaling currents is well-known in the art and has no bearing on the present invention.

The invention will be more readily understood from the following detailed description and the appended claims.

The subscriber located at substation 100 desiring to obtain a connection with one of the parties, *e. g.* 200 of a four party telephone line, removes his receiver from the switchhook for causing the displaying of a signal 101 in the well-known manner. An

operator inserts thereupon an answering plug 102 into an answering spring jack 103 for extinguishing signal 101 and for taking the orders of the calling subscriber. She then sets up the number of the desired party line on a well-known revertive impulse sender 104 for controlling selector switches 105, 201 and 202 to select the desired line. A sequence switch (not shown) associated with the selector 105 controls sequence switch springs 106, 107 and 108. During the setting of the selectors this sequence switch is in position 11, and the extent of travel of the selector switches is controlled by the successive opening and closure of a contact 109 provided in a controlling circuit at sender 104, and a stepping relay 110 controls the stepping of the sender in accordance with impulses sent from the switches back to the sender. As such selector switches and their circuit arrangements are well known in the art and as they do not form a part of the present invention, their detailed description does not seem necessary. Sequence switch spring 108 controls the holding of the selected trunk during conversation. After the selector switches have been set, the top contacts of the sequence switch springs 106 and 107 are closed for extending the calling to the called line.

The selection of the proper ringing current takes place now. Contacts 203 and 204 of a sequence or side switch (not shown), associated with and controlling selector 201, are set into their second position, and further, a relay 205 becomes energized. A circuit is closed from ground, through the armature and front contact of relay 205, and the winding of relays 206 and 207, to grounded battery. Only relay 207 becomes energized, a shunt being closed around the winding of relay 206. Relay 207 closes the ringing circuit for station 200 from ground through contact spring 203, the upper front contact and armature of relay 207, wiper 208 of connector 202, line conductor 209, the substation 200, line conductor 210, brush 211 of connector 202, the lower armature and front contact of relay 207, sequence switch spring 204, conductor 212, the left-hand winding of a relay 213 and a positive superimposed on alternating ringing current source 214, to ground. Upon the removal of the receiver at the called station, relay 213 becomes energized, opens at its front contact the shunt

around the winding of relay 206 which then becomes energized, short-circuits relay 207 and closes a locking circuit for itself.

If connection is desired to substation 220, 5 sequence switch springs 203 and 204 are moved into their third position, in which case the ringing circuit of the called station is closed through the right-hand winding of relay 213 and a negative superimposed 10 on alternating ringing current source 221 for applying a characteristic ringing current for station 220. If station 222 is desired, sequence switch springs 203 and 204 are moved into their fourth position, and 15 the ringing current source 214 is connected through sequence switch spring 203 to the line conductor 209, and ground is connected through sequence switch spring 204 to the line conductor 210 for ringing this station. 20 If station 223 is desired, sequence switch springs 203 and 204 are moved into their fifth position for connecting ground to the line conductor 210 and ringing current source 221 to line conductor 209.

25 If one or a plurality of these stations 200, 220, 222 and 223 are disconnected from this party-line and associated with another line, it is desirable to extend the incoming call to an operator's position 300 in order that 30 this operator may inform the calling party of the new number of the desired party.

There is shown in Fig. 3 an arrangement for taking care of the signaling to the operator of the existence of such intercepted 35 call. As has been described, the various stations associated with the same party line may be selectively rung. To ring station 200, positive superimposed on alternating current is impressed upon conductor 210; 40 for station 220, negative superimposed on alternating current is applied connected to line conductor 210; for station 222, positive superimposed on alternating current is applied to line conductor 209, and for ringing 45 station 223, negative superimposed on alternating current is applied to line conductor 209. The apparatus shown in Fig. 3 may be wired in such a manner that a ringing current sent to any of these substations may 50 be intercepted to signal an operator positioned at 300.

If station 200 is disconnected, the M wiring is used, *i. e.*, wires M are installed to interconnect terminal points 301, 302 and 55 303, 304 respectively. If station 220 is disconnected, the N wiring is used, *i. e.*, wires N are installed to interconnect terminal points 301, 304 and 302, 303 respectively. If both these stations are disconnected, W wiring is used, *i. e.*, wire W is installed to connect conductor 315 with terminal point 301. In the same manner, if station 222 is disconnected X wiring, if station 223 Y wiring, and if both these latter mentioned stations 60 are disconnected Z wiring is used.

Supposing that ringing current is applied to line 210 for signaling a disconnected station 200, it will be seen that a circuit is established from ground through condenser 310, the winding of an alternating current 70 relay 311, conductor 312, line conductor 210, connector brush 211, lower armature and front contact of relay 207, sequence switch spring 204, the left-hand winding of relay 213, and positive superimposed on alternating current source 214, to ground. Relay 311 closes a circuit from ground through its front contact and armature, wire M, the windings of a polarized relay 313, wire M, resistance 314, and then in parallel with relay 311 to ground through current source 214. Relay 313 becomes energized and closes a circuit from ground through its armature and front contact, conductor 315, the winding of relay 316, the back contact 80 and armature of relay 317, lamp 318, and the winding of relay 319 to grounded battery. Lamp 318 is lighted and relay 319 closes a circuit for operating a bell 320 to call the attention of the operator to the fact that 90 an intercepted call has to be answered. Relay 316 closes a circuit from grounded battery through conductors 312 and 210, brush 211 of selector 202, lower armature and front contact of relay 207, sequence switch 95 spring 204, conductor 212, left-hand winding of relay 213, current source 214 to ground for energizing relay 213. Relay 213 causes the deenergization of relay 207 in the above described manner. Upon the reaction of relay 207, the circuit of relay 213 is opened and this relay again becomes deenergized. The operator at position 300 inserts a plug 321 into a spring jack 322 and depresses a listening key 323, extending her telephone 100 set to the calling incoming line. Relay 317 is energized by a circuit from battery, through the winding of this relay, the sleeve contacts of spring jack 322 and plug 321, and through a resistance 324 to ground. Relay 317 opens the circuit of lamp 318 and relay 319, which in turn disconnects bell 320. The operator inquires now which station 110 was wanted and gives the necessary indications for extending the calling subscriber's line to the desired station.

Ringing current applied to the called line for signaling station 220 will not actuate signals 318 and 320, due to the fact that polarized relay 313 does not become energized if negative superimposed on alternating current flows through its lower and upper windings to ground. If, however, station 220 is disconnected and the apparatus in Fig. 3 is wired in accordance with N wiring, the negative superimposed on alternating current source 221 is connected through wire N, the upper and lower windings of relay 313 to ground. This relay becomes 120 energized and causes the displaying of the 125 130

signals at the operator's position. Relay 311 responds to currents supplied to its winding from both sources 214 and 221.

If both stations 200 and 220 are disconnected, the apparatus is wired in accordance with W, and therefore, upon the energization of relay 311, relays 316 and 319 and lamp 318 will immediately become energized for causing the signaling of the operator.

10 If station 222 is disconnected, upon the ringing of this station the signaling of the operator is accomplished in substantially the same manner as above described. An alternating current relay 330 becomes energized for causing the closure of a circuit from ground through its front contact and armature, wire X, and the windings of polarized relay 331, wire X, resistance 332, conductor 333, line conductor 209, brush 208, the upper 15 armature and front contact of relay 207, sequence switch spring 203, the left-hand winding of relay 213, and the current source 214, to ground. Polarized relay 331 becomes energized and closes an energizing circuit 20 for relays 334, 319 and lamp 318 for signaling the operator at position 300. Ringing current impressed upon the lines 209, 210 for signaling station 223 will not affect polarized relay 331 unless the apparatus is 25 wired in accordance with Y. If both stations 222, 223 are disconnected, the Z wiring is used and thus signals 318 and 320 are operated under the control of relay 330. The operator at station 300 and the calling 30 subscriber are supplied with current through the armatures and front contacts of relays 316 or 334.

What is claimed is:

1. In a telephone system, a multi-party 40 telephone line including a metallic conductor, a plurality of sources of ringing current each of a different character, means for selectively applying said currents to said line, a relay responsive to any of said ringing currents connected to said conductor, a relay controlled by said first relay, a signal controlled by said second relay, and means controlled by said second relay for controlling the flow of said ringing currents.

50 2. In a telephone system, a multi-party telephone line comprising two metallic conductors, a plurality of sources of ringing current each of a different character, means for selectively applying said currents to said line, a relay responsive to any of said ringing currents connected to a single one of said conductors of said line, a relay responsive to a particular one of said currents connected to the same conductor and controlled by said first relay, a signal controlled by said second relay, and means controlled by said second relay for controlling the flow of said ringing currents.

55 3. In a telephone system, a multi-party telephone line comprising two metallic con-

ductors, a plurality of sources of ringing current each of a different character, means for selectively applying said current to said line, a relay responsive to any character of ringing current connected to a single one of 70 said conductors, a relay responsive to a particular one of said ringing currents connected to the same side of said line and controlled by said first relay, a third relay controlled by said second relay, a locking circuit for said third relay, a signal in circuit with said third relay, and means controlled by said third relay for controlling the flow of said ringing currents.

4. In a telephone system, a multi-party 80 telephone line comprising two metallic conductors, a plurality of sources of ringing current each of a different character, means for selectively applying said currents to said line, a relay responsive to any character of 85 ringing current connected to a single one of said conductors, a relay responsive to a particular one of said ringing currents connected to the same conductor of said line and controlled by said first relay, a third relay 90 controlled by said second relay, a locking circuit for said third relay, means controlled by said third relay for applying a characteristic electrical potential to said conductor, and means responsive to the application of said 95 potential for controlling the flow of said ringing currents.

5. In a telephone system, a multi-party 100 telephone line, two sources of ringing current of different character, an electromagnetic means operable by current from a single one of said sources of current, means operable by current from both of said sources of current for associating said electromagnetic means with said line, and a signal controlled by said electromagnetic means.

6. In a telephone system, a line, a plurality 105 of substations on said line, a signaling device at each of said substations, a variably operable signaling means for selectively operating said signaling devices, two relays connected one to each side of said line and each responsive to all currents applied to its side of said line, two relays controlled one by each of said first relays respectively and connected one to each side of said line, each of said last mentioned two relays being responsive to a particular current, and a signal controlled by either of said second relays.

7. In a telephone system, a line, a plurality 110 of sources of different signaling current adapted for selective association with said line, a relay connected to said line responsive to a particular one of said currents, said relay being connected in a normally 115 open circuit, means responsive to any of said currents for closing said circuit, and a signal controlled by said relay.

8. In a telephone system, a line, a source 120 of signaling current, means for variably as-

sociating said source of current with the limbs of said line, a relay associated with said line and responsive to signaling current flowing in one direction, a circuit for 5 said relay, means responsive to signaling current flowing in either direction for controlling said circuit, and a signal controlled by said relay.

9. In a telephone system, a line, a plurality 10 of telephone stations bridged across said line, a polarized magnet at each of said stations, the magnets at two stations being connected between ground and one side of said line, and the magnets at the other stations 15 between ground and the other side of said line, two current sources, one producing negative superimposed on alternating current and the other positive superimposed on alternating current, means for variably asso-

ciating said current sources and ground with 20 one or the other sides of said line, an alternating current relay connected between ground and one side of said line, another alternating current relay connected between ground and the other side of said line, a 25 grounded front contact for each of said relays, a polarized relay connected between the armature of one of said alternating current relays and one side of said line, another polarized relay connected between the armature of the other alternating current relay and the other side of said line, and a signal controllable in response to the actuation of any one of said relays.

In witness whereof, I hereunto subscribe 35 my name this 24th day of September A. D. 1915.

ALBEN E. LUNDELL.
